GEORGE H. SCHIFFMACHER

INVENTOR

Edward C. Schiffmacher
BY
ATTORNEY

UNITED STATES PATENT OFFICE.

GEORGE H. SCHIFFMACHER, OF EAST ROCKAWAY, NEW YORK.

TENT-FRAME.

1,314,758.

Specification of Letters Patent. Patented Sept. 2, 1919.

Application filed February 11, 1918. Serial No. 216,508.

To all whom it may concern:

Be it known that I, GEORGE H. SCHIFFMACHER, a citizen of the United States, residing at East Rockaway, county of Nassau, State of New York, have invented certain new and useful Improvements in Tent-Frames; and I do declare the following to be a full, clear, and exact description of my invention, such as will enable others skilled 10 in the art to which it pertains to make and use the same, reference being had to the accompanying drawings, which form a part of this specification.

My invention relates to new and useful 15 improvements in the construction of portable or knock-down tent frames and consists of the matters hereinafter described and pointed out in the appended claim. My invention is particularly applicable to all standard or 20 regulation sizes of Government tents for army use and for tents for camping purposes. It is used in connection with tents by placing the tent over the frame and fastening the tent to the ground by pegs and 25 rope or guys in the usual manner.

The object of my invention is to provide a tent frame of strong, light construction which can be quickly and easily taken apart and put together and which will render a 30 tent warm, dry and able to withstand heavy winds without blowing down.

In the accompanying drawings illustrating my invention: Figure 1 is a perspective view of a tent frame for regulation army officer's tent, constructed in accordance with 35 my invention showing part of the water-proof canvas or like material with which the front, sides and lower back sections of the tent frame are covered. Fig. 2 shows a 40 crate or box composed of the floor shown in Fig. 1, the sides of the tent frame being foldable with the floor and the whole forming a box or crate into which the tent and all the sections of the tent frame constructed 45 in accordance with my invention will fit. Fig. 3 shows the upper portion of the back of the tent frame showing the oblique roof supports and the brace for same and illustrating the manner in which the brace 50 and the oblique roof supports fold so as to be practically parallel with the ridge pole support for shipment. Fig. 4 is a front view partly in elevation and partly in plane of the right hand front corner of the tent 55 frame shown in Fig. 1. Fig. 5 is a side view of the same corner shown in Fig. 4.

Fig. 6 is a sectional view of the corner shown in Figs. 4 and 5 taken on the dotted line 11—11 in Fig. 5. Figs. 4, 5 and 6 show in detail the method of attaching the frame members together and the method of joining the sections together.

Referring by numerals to the said drawings, 1 is the floor, 1' are floor supports. The floor 1 as shown in Fig. 1 is foldable with the side sections of the tent frame into four parts, the side sections being attached to the floor by hinges 2, Figs. 1 and 4, and the sections of floor being joined together with hinges 2 as shown in Figs. 1 and 2. In the 70 hinges used for this purpose I use slip pins or cotter pins so that sections are detachable without removing hinges from members to which they are attached. 3 are vertical members of frame sections. 4 are the lower 75 horizontal members of frame sections. 4' are horizontal frame members constituting the upper horizontal parts of the lower frame sections. 4² are the lower horizontal members of the left and right upper front 80 sections. 4³ are the upper horizontal members of the left and right front upper sections. 5 are oblique braces used in lower frame sections. In the particular form of construction shown in Fig. 1, the members 85 of the frame sections are joined together by metal plates 19, 20, 21 and 40, bolted through the frame members, as shown in detail in Figs. 4, 5 and 6. In constructing the front sections as shown in Figs. 1, 4, 5 and 6 and 90 where no oblique braces are used, I join the horizontal members 4 and 4' to the vertical members 3 by use of metal corner plates 20, using plates on both sides of the frame members and bolting through the frame and the 95 plates with stove bolts 41 as shown in Figs. 4, 5 and 6. In constructing frame sections where oblique braces are used as in Fig. 5, I join the vertical members 3 and the horizontal members 4 and 4' by using metal 100 plates 40 on the top and bolting the frame members as shown in Figs. 4, 5 and 6 and metal plates 19 on the bottom and bolting through the frame members. The lower horizontal members 4² of the upper right 105 and left front sections are joined to the oblique frame members 11 by metal plates 21 and bolts substantially as shown in Figs. 1, 4 and 5. 6 are vertical members of door frame—Fig. 1. 7 are horizontal members 110 of door frame—Fig. 1,—6 and 7 being joined at upper and lower corners by metal

corner plates substantially the same as 20 bolted through the door frame members. 25' are metal hangers attached to door frame upon which to hang door—Fig. 1, 5 an ordinary blind hinge or similar suitable hinge being used for this purpose. 8 are horizontal and 9 are vertical members of door, Fig. 1, the lower section of the door in practice being covered with waterproof 10 canvas or like material tacked on or otherwise suitably attached or applied to the frame and the upper section having inserted therein a window 10 composed of small panes of flexible celluloid or like material stitched 15 into a canvas or cloth frame and buttoned on or otherwise suitably detachably attached to the door frame or placed over the window aperture on a roller so as to roll up and down over opening. An additional window 20 10' is likewise inserted in front section as shown in Fig. 1. 11 are oblique members of upper front sections supporting ridge pole 12, the ridge pole being braced by oblique braces 13—Fig. 1, suitably attached by 25 metal plates and bolts.

14 is a vertical member of upper rear section, forming rear support for ridge pole 12 and supporting rear oblique rafters or supports for rear of tent—Fig. 3. The 30 oblique rafters 15 are attached to vertical support 14 at its upper end by metal plate 43 and bolts, substantially as shown in Fig. 3. By detaching 15 at their lower ends and detaching brace 16 at 22 the rafters 15 35 swing upon the bolts by which they are attached at 43, and the brace 16 rotates upon bolt at 23 so that all are practically parallel with 14 for shipment. 17 shows swinging or foldable bracket supporting shelf—Fig. 40 1. Shelf 39 is constructed along both sides and back of tent frame as shown in Fig. 1 and is so arranged by means of hinges 18 on vertical frame members as to fold down flat against the back and sides of tent 45 frame when sections are detached for shipment. When in horizontal position and supported by brackets 17 at suitable places on vertical frame members it forms a substantial brace for the tent frame and adds 50 to its rigidity. 19, 20, 21 and 40 are metal plates used in fastening frame members together substantially as shown in Figs. 1, 4, 5 and 6, plates being placed on both sides of frame members and bolted together, 55 through the frame members by means of stove bolts 41, substantially as shown. 24 are long stove bolts used as shown in Fig. 1 in fastening together the frame sections. 44 shows covering of waterproof canvas, 60 oil cloth or like material suitably applied to lower frame section—Fig. 1. In constructing a tent frame as shown in Fig. 1,

I cover all the lower sections of the frame and the upper front sections with waterproof canvas, oil cloth or like material, by 65 lacing, tacking on or otherwise suitably attaching the material to the frame sections. I prefer to attach the covering so that it can be easily removed for ventilation or be replaced by screening in warm weather. 70

A tent supported by a frame constructed in accordance with my invention as described, with sections covered and door and windows inserted as described is rendered 75 warm, dry and weather proof. It is strong 80 and rigid enough to be moved without taking it apart or if necessary the frame can be quickly taken apart either in sections as shown or can be knocked down by removing bolts and the frame and tent packed in box 85 formed by foldable floor for shipment. The frame has the advantage of being very light, the tent and frame packed for shipment weighing much less than a portable wooden structure of the same size. The frame can 90 be quickly and easily erected and does not suffer damage from being taken apart and put together if ordinary care is used. The tent frame can be used without floor as well 95 as with floor.

In constructing the tent frame all outer edges of frame members which come in contact with the tent when placed over the frame are rounded and rendered smooth as shown in Figs. 4 and 5 so as not to chafe 95 and wear the tent.

Having thus described my invention; what I claim as new, and desire to secure by Letters Patent is:

In a tent frame,—vertical, horizontal and 100 oblique frame members detachably joined so as to form frame sections,—frame sections detachably joined to form tent frame, a floor in sections foldable with the side frame sections so as to form a box or crate 105 to contain the entire frame and tent, tent roof supporting frame members composed of a ridge pole supported in front by oblique front section rafters and upper front sections, and in the rear by vertical central 110 frame member and oblique rafters suitably attached to rear corners of tent frame and foldably attached to top of vertical supporting member; frame members rounded 115 on their outer edges to prevent chafing tent, substantially as described.

In witness whereof, I have hereunto set my hand in the presence of two subscribing witnesses.

GEORGE H. SCHIFFMACHER.
